CLAIM

The ornamental design for a curtain carrier as shown and described.

DESCRIPTION

FIG. 1 is a top perspective view of the first embodiment of a curtain carrier, showing my new design;

FIG. 2 is a bottom perspective view of FIG. 1;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top view of FIG. 1;

FIG. 8 is a bottom view of FIG. 1;

FIG. 9 is a cross-sectional view of FIG. 1, taken along lines 9-9 in FIG. 7;

FIG. 10 is a cross-sectional view of FIG. 1, taken along lines 10-10 in FIG. 7;

FIG. 11 is a top perspective view of the second embodiment of a curtain carrier;

FIG. 12 is a bottom perspective view of FIG. 11;

FIG. 13 is a front view of FIG. 11;

FIG. 14 is a rear view of FIG. 11;

FIG. 15 is a left side view of FIG. 11;

FIG. 16 is a right side view of FIG. 11;

FIG. 17 is a top view of FIG. 11;

FIG. 18 is a bottom view of FIG. 11;

FIG. 19 is a cross-sectional view of FIG. 11, taken along lines 19-19 in FIG. 17; and,

FIG. 20 is a cross-sectional view of FIG. 11, taken along lines 20-20 in FIG. 17.

The broken lines in the drawings show portions of the curtain carrier that form no part of the claimed design.

1 Claim, 10 Drawing Sheets
